UNITED STATES PATENT OFFICE.

WARNER R. BUXTON, OF LONGMEADOW, MASSACHUSETTS.

COIN PURSE.

Application filed June 24, 1924. Serial No. 722,127.

This invention relates to improvements in coin purses.

The invention is a development of that disclosed in my copending application Serial No. 722,128, filed June 24, 1924. The purse disclosed in said application is characterized by an inner piece of rather stiff material which is constructed to bend readily along certain predetermined lines and according to 10 a definite plan. This inner member is mounted in an outer case or envelope and forms the bottom or floor of a tray purse. The arrangement is such that, when the middle portion of the purse is pressed with the 15 fingers, the inner member will bend down into deep trough like form and so that the coins may readily slide out of the pocket and be spread out on the tray of the purse.

One object of this invention is to improve 20 the tray construction by the provision of flap extensions on the inner member which are made to cooperate with the marginal wings of the tray and cause the same to be raised upwardly when the inner member is bent 25 downwardly into the form described.

Another object of the invention is to improve 30 the construction of the outer case or envelope to the end of securing greater freedom for the bending action of the inner floor member and greater range for the bending movements thereof.

Other objects and advantages will appear 35 in the following description and in the illustrative embodiment of the invention in the accompanying drawings, in which:—

Fig. 1 is a top plan view of an open tray purse embodying the invention;

Fig. 2 is a side elevational view thereof;

Fig. 3 is an enlarged, fragmentary, cross-sectional view taken on the line 3—3 of Fig. 1;

Fig. 4 is a cross-sectional view taken on the line 4—4 of Fig. 1 showing the purse bent by pressure applied to its sides;

Fig. 5 is a small scale top plan view, taken similarly to Fig. 1, but showing the purse when bent by the application of pressure to its sides;

Fig. 6 is a fragmentary cross-sectional view taken on the line 6—6 of Fig. 1, showing the normal position of the tray and its side wings;

Fig. 7 is a view similar to Fig. 6, but showing the positions assumed by the bottom of the tray and its side wings when pressure is applied to the sides of the tray purse;

Fig. 8 is a view taken similarly to Fig. 1, but showing a modification of the invention;

Fig. 9 is a developed view of the blank from which the inner lining member is 60 made;

Figs. 10 and 11 are cross-sectional views taken on the lines 10—10 and 11—11, respectively, of Fig. 8;

Fig. 12 is a view taken similarly to Fig. 65 1 but showing a further modification of the invention;

Fig. 13 is an elevational view of one side of the tray purse shown in Fig. 12;

Fig. 14 is a fragmentary elevational view 70 of the opposite side of the tray purse; and

Fig. 15 is an elevational view showing the purse in its folded position.

Referring to these drawings and particularly to Figs. 1 to 7 inclusive; the specific 75 coin purse illustrated (generally referred to as a tray purse) includes an envelope or outer case A, made of readily flexible material such as leather or the like, and an inner member B, which is made of much heavier and less flexible material, such as relatively thick leather or the like. The construction of the outer case A follows more or less conventional lines and a detailed description of its constructional features will 80 be postponed until the construction and operation of the inner member B has been explained.

This inner member is the foundation and unique feature of the tray purse. It consists of a substantially rectangular piece of rather stiff leather and its outline, when in the purse, may be seen by following the dotted line 16 in Fig. 1. The member B is cut through with a sharp knife along a central 95 line 17 from one end up to a point 18, which is a little over half way from such end. Two diverging cuts 19 and 20 are made from the point 18 to points 21 and 22. Each of these points 21 and 22 are about equally 100 spaced from each other and from the adjacent corners of member B. As shown, this end of the member is cut in, or back, so that the central portion, where points 21 and 22 are located, is spaced from the adjacent end of case A. Thus, the member is provided with ears 23 which extend outwardly from points 21 and 22 toward the adjacent corners of the case. The opposite end of member B is preferably cut back and provided 110 with similar ears 24. With the member B, cut as described, a very thin leather facing

25 is applied with adhesive to one face thereof,—being the outer face as viewed in Fig. 1.

This construction permits a flexible hinge 5 action along the lines of the cuts. These cuts are made squarely with the face of the leather piece B and with a sharp instrument so that the walls of the cut will lie substantially contiguous and abut when the 10 piece is flat. The thin leather facing 25, by means of which the cut sections of the piece B are joined together on one face, together with the thick square walls along the cuts of piece B, tend to strongly retard any bending 15 action except that which uses the facing 25 as a hinge along the lines of the cuts, when the member is bent into a predetermined trough-like shape. It is clear that, with this construction, if the member B is 20 grasped between the fingers near its middle portion and pressed inwardly, the whole piece will immediately bend, due to the hinged arrangement described, into the form shown in Figs. 4, 5 and 7.

25 The right hand portion of member B is provided with the two diverging cuts so that this portion will bend into shovel formation whereas the left hand portion is provided with only one cut so that it will 30 bend into V-shaped formation. In this bending action, the object sought is to provide sloping walls to cause the coins to be 35 spread upon the surface of the shovel shaped portion.

The member B forms the bottom or floor 40 of a tray purse and to this end fits within a back piece 26 and superimposed on the left hand portion thereof are two pieces 27 and 28, which are secured thereto along one end 45 and both sides, as by stitchings 29, thereby forming a coin pocket 30 between the pieces 26 and 27 and another pocket between the pieces 27 and 28 for the reception of small 50 cards, postage stamps and the like. A flap 30', provided on the piece 27, is folded over the piece 29 and normally closes the last 55 named pocket. That portion of the back piece 26 not covered by the pieces 27 and 28 forms the tray portion of the purse and communicates with the pocket 30. The tray portion is embordered with side and end wings 31 and 32 to prevent the coins from 60 escaping from the tray as they slide out of the pocket 30 upon the shovel shaped floor of the tray.

The parts described are thus assembled to 65 form a coin purse embodying the invention of the application above referred to. When the purse is opened, as in Fig. 1, and the middle portion is pressed together, as indicated in Fig. 5, the stiff member B immediately bends in the intended manner and 70 the floor of the pocket 30 falls down into

trough like form and the floor of the tray into shovel shaped form. As a consequence, the coins slide out of the pocket and are spread out and displayed on the tray for 75 convenient selection. In connection with this action, the object of cutting back the ends of the member B from the ends of the outer case is to give freedom for the downward movement. These ends, if wedged in 80 between the upper and lower parts of case A 75 at its ends, would be held against bending and would in turn tend to restrict the degree of bending of the intermediate portions of member B. As constructed, the end of the member disposed on the bottom of pocket 85 30 bends down but not to so great a degree as the member bends near the mouth of the pocket (see Fig. 4) so that the floor of pocket 30 slopes downwardly from its closed end to 90 ward its open end.

The action of the member B in bending 95 downwardly is controlled by the back portion 26 of the outer case, which exerts a restricting influence thereupon. This influence is proportional in degree to the degree 100 of stiffness of the back piece 26. As a practical matter, a very thin, soft leather is ideal for the back piece but in practice is not satisfactory as the outer face of the case. As a feature of this invention, I construct the piece 26 of thin, soft, readily pliable leather to improve the action of the purse by lessening the restricting influence 105 of the back piece on the bending of the member B and, in order to provide a suitable 110 wearing face for the back of the purse, I provide a second back piece 33 of greater 115 length than the piece 26. Sufficient slack 120 in the piece 33 is provided so that the piece 26 can move downwardly without restriction and, in furtherance of this object, the 125 piece 33 which is secured at its ends to the piece 26 is secured thereto along only one 130 of its two sides. The slack in the stitched 135 side of the outer back piece 33 is all left at 140 the middle portion which is unsecured, as 145 shown at 34 in Fig. 2. This construction 150 permits the use of a more serviceable leather 155 as an outer wearing face of the case and at 160 the same time avoids the restricting influence 165 on the bending action of member B which would exist if such sort of leather 170 were used for the inner back 26. The latter 175 can be made of the very soft, thin material 180 desired and be protected by the more serviceable outer back 33.

The wings 31 and 32, as shown, are integral 185 portions of the outer back piece 33 and are made from a substantially U-shaped 190 portion thereof which is bent over the right 195 hand end of the purse and secured along the side edges of the latter, as by stitchings 34. In the case of the end wing 32, the inner 200 back piece 26 has an extension 35 which is 205 brought up in under the wing as shown in 210

Fig. 3. These end extensions of the pieces 26 and 33 are both turned inwardly, over the cross bar portion of a U-shaped wire 36, and secured by adhesive in the positions shown in Fig. 3. The two leg portions of this U-shaped wire extend along the inner edges of the side wings 31, as indicated in Figs. 1 and 6.

As a feature of this invention, I provide flap extensions 37 of the floor member B, one on each side thereof, which are turned upwardly and underlie the side wings 31. These extensions are secured to the wings by adhesive and this fastening of the member B to the case is the only fastening employed. The member B is free to slide back and forth in the pocket 30, as may be necessary, when the tray portion is folded upon the pocket portion to close the purse. It will be seen that, in the action of pressing the case together near its middle portion to depress the floor member B into trough like form, there is an additional action due to the connection of the flap extensions 37 with the wings 31. As the floor member B bends downwardly, the flap extensions naturally bend upwardly and raise the wings 31 to a greater distance above the floor of the tray. The elevation of the wings automatically occurs at the time when needed, being caused by the depression of the floor, which causes the coins to slide out upon the tray.

The raising of the wings 31 naturally occurs to a greater degree near their free ends, or in other words, nearest the location at which pressure is applied to the sides of the purse. The U-shaped spring wire 36, however, tends to transmit the raising action all along the wings 31 and along the end wing 32. It also assists in the raising of the side wings by holding their inner edges while their outer edges move inwardly under the pressure on the sides of the purse. The inner edges being held against inward movement are obliged to move upwardly as the outer edges move inwardly. The wire 36 is desirably rounded and unsecured to any portion of the wings in the sense that the latter can turn on the rod during the action described. The wire 36 also has some tendency to cause the parts of the purse to return to normal position after the pressure on its sides is relaxed.

The purse, when closed and in the condition in which it is carried in the pocket, is shown in Fig. 15. The tray section is folded over upon the pocket section in the usual manner. In Fig. 2, I have shown a flap 39 on one end of the purse carrying one section 40 of a snap fastener, which when the purse is closed can be engaged with another fastener section 41, carried by the outer back piece 33.

The specific and preferred form in which the invention has been disclosed may be va-

ried widely without departing from the scope of the invention. For example, the member B may be cut in many other ways and still function in the same general manner. The arrangement whereby a flat central portion is formed in the floor of the tray, when depressed as described, is desirable, important and preferred but the results of the invention can be obtained to a degree, if this feature is omitted, as shown in Fig. 8. Here the member B is provided with a single central cut 42 which extends nearly from end to end and terminates just short of the end wing 32 at a hole 43. From the latter diverging cuts 44 are made to the adjacent corners of member B, leaving a triangular section 45, which forms a sloping wall at the end of the tray when the floor thereof is depressed. The flat portion for the central part of the floor of the tray may also be obtained in various other ways, one of which is illustrated in Fig. 12 wherein the member B has two spaced, longitudinal cuts 46. When the floor of this member B is depressed, a central flat portion 47 will be formed between the sloping side walls and this portion may, if desired, extend from end to end of the purse, as shown. In Fig. 12, the end of member B adjacent wing 32 is cut back as described in connection with Fig. 1, forming ears 23, but the space between these ears is covered by extending the thin leather facing 25 in under the wings. This expedient is used to insure against coins working their way in under member B, where the space between the end of member B and the adjacent end of the tray is larger than the smallest coin used, as it is in Fig. 12.

The connection of flap extensions of member B with the side wings 31, as described in connection with Fig. 1 serves also to raise the end wing 32 by reason of the U-shaped wire 36. While this arrangement is preferred and is the most effective for its purpose, the results of the invention, at least in part, can be obtained by other arrangements differing specially in form. For example, as shown in Fig. 8, the wire 36 may be omitted and reliance placed wholly upon the flap extensions 37, supplemented if desired by an end flap extension 48 which is connected with the end wing 32 to reinforce the same and tend to raise it when the floor of the tray is depressed.

The provision of the outer back piece 33 is a feature of invention capable of use independently of the other inventive features and may be omitted, as shown in Figs. 8, 10 and 12, although it is important and preferred for the reasons above stated.

So also the manner, in which the member B is weakened to bend along predetermined lines according to a definite plan, may be varied within wide limits. There are many

other known methods of weakening which, if used, would permit the results of this invention to be obtained to a degree although that method specifically disclosed herein has proved most satisfactory in service and is therefore preferred.

The member B may, to advantage, be made to line both walls of pocket 30, as shown in Fig. 10. In such case, member B is provided at one end with side flaps 50 which are folded along the dotted lines shown in Fig. 9 and their edges brought together as shown in Fig. 10, being held, as described, by the thin leather facing to form 15 a hinge connection. This construction insures a full, wide opening for the mouth of pocket 30 and also increases the tendency of the floor of the tray to bend downwardly in the intended way.

20 In operation, the two sections of the purse, which are normally positioned one above the other as shown in Fig. 15, are moved into the relative positions shown in Fig. 1, in which the tray lies in extended relation 25 with, and in continuation of, the coin pocket 30. The purse, when thus opened, is usually held in the palm of the hand with the thumb and one finger grasping the sides of the purse near its central portion. Pressure on 30 these sides is applied by moving the thumb and finger toward one another and on the application of such pressure, the purse takes a form somewhat like that shown in Fig. 5. On the application of pressure, the outer 35 edges of member B are forced toward one another and, since the sections of this member are so hinged as to move toward the back piece 26 or downwardly (as the purse is held in the hand), the floor of the pocket 40 30 assumes the position shown in Fig. 4 and the floor of the tray assumes the position shown in Fig. 7. The coins gravitate down the outwardly sloping floor of the pocket 30 and issue from the mouth thereof 45 onto the tray, even though the purse be held horizontally. A slight elevation of the pocket above the purse is, however, ordinarily employed. The bending of the floor 50 of the tray makes its central portion very deep and renders it difficult for coins to escape by riding up over the wings 31 or 32. The sloping side walls of the floor of the tray tend to prevent such action with respect to wings 31 and the end of the tray adjacent wing 32 assumes a similar position 55 and performs a similar function. The flat section of the tray naturally receives the bulk of the coins and they are thus more or less centralized so as to be accessible for convenient selection. If this section happens to be filled with coins, other coins will 60 rest on the adjacent sloping sections and the arrangement is such as to cause the coins to be spread out and distributed over the

tray rather than bunched in one particular location.

The bending action, described, also causes the wings 31 to tilt upwardly and to a greater degree near the points of application of pressure than near their junction 70 with wing 32. This condition is illustrated in Fig. 7. This action follows from the inward movement of the flap extensions 37 at one end of their hinge line of connection with member B. While such edges move 75 inwardly, their upper edges are tied together at the opposite end by the end wing 32 and cannot move inwardly. Consequently, due to the pressure and to the restraining action of the end wing, the side wings near 80 their free ends tilt upwardly. This action is intensified if the spring wire 42 is used. The latter also tends to restore the parts to normal position on the relaxation of pressure on the sides of the purse. Previous to 85 the relaxation of pressure, the purse is tilted so as to allow the coins in the tray to slide back into the purse, after which the side pressure is relaxed and the tray folded over upon the purse, as shown in Fig. 15. 90

The invention is characterized by the provision of an inner member for the tray arranged to bend in a predetermined manner and more easily and to a greater degree than it otherwise would. This inner member is associated with an outer casing which can be made of the fine, soft, thin leathers which have not, of themselves, sufficient substance to function alone in the desired way. A better appearing tray purse, and one 10 which functions in a materially improved way, is provided by the use of the two materials, neither one of which has heretofore proved commercially satisfactory. The bending of the floor of the tray occurs in a predetermined manner according to a definite plan and the bending is far more readily accomplished and occurs to a greater degree than in any other tray purse of which I am aware. At the same time, the purse is kept in a thin compact form which is desirable to enable it to be comfortably carried in the pocket. Aside from the spring wire described there are no metal parts, the presence of which ordinarily adds weight and bulk to the case. The spring wire is, however, small and of light weight and its presence in the case hardly noticeable.

The invention has been disclosed herein, in an embodiment at present preferred with detailed variations, for illustrative purposes, but the scope of the invention is defined by the appended claims rather than by the foregoing description.

What I claim is:

1. A coin purse, comprising a casing of flexible material forming a coin pocket and a tray foldably connected therewith, said

casing having a double back comprising an inner back of soft, readily pliable material forming the bottom of the pocket and tray and an outer back of flexible but less pliable material forming an outer wearing surface, and a relatively stiff member disposed within the casing and made up of hinged sections constructed to bend toward said inner back when pressure is applied to the sides of said casing, said outer back being larger than the inner back and spaced therefrom to permit free downward movement of said member and inner back.

2. In a coin purse, a casing comprising an inner back piece of soft readily pliable material, a front piece of flexible but less pliable material applied over the back piece to provide a coin pocket and connected tray with marginal wings, and secured along its edges to said back piece, a second back piece of flexible but less pliable material than the first named back piece and of greater length, said back pieces being secured together at their ends and partially along one side with the other side completely free leaving slack in the outer back piece intermediate its ends, and an inner member of relatively stiff material forming a floor for said pocket and tray and made up of a plurality of hinged sections constructed to bend in a predetermined manner toward said inner back when pressure is applied to the side walls of the casing.

3. In a coin purse, a casing of flexible material forming a coin pocket and connected tray, and a member of relatively stiff material forming a floor for said pocket and tray, said member being cut through from end to end along a plurality of longitudinal lines and having a thin flexible facing secured to its inner face, whereby the cut sections are hinged together to bend along the lines of said cuts and depress the floor of said tray into deep trough like form when pressure is applied to the sides of the outer case.

4. In a tray purse, a tray section comprising a member having wings embordering its margins, a member of relatively stiff material applied over the first named mem-

ber forming a floor for said tray, said member comprising a plurality of hinged sections constructed to bend downwardly into trough like formation when pressure is applied to the sides of the tray, and extensions from the side edges of the floor member bent upwardly to underlie certain of said wings.

5. In a coin purse, an outer casing of flexible material forming a coin pocket and connected tray, flexible wings embordering the sides and outer end of said tray, a member of relatively stiff material loosely applied to one face of said pocket and tray and made up of sections hinged to bend toward said face when pressure is applied to the sides of the casing, and extensions on said member bent up from its side edges to underlie said wings, said member extending into said tray but terminating in spaced relation with the bottom of the pocket and the outer end of the tray.

6. In a coin purse, an outer casing of flexible material forming a coin pocket and connected tray, flexible wings embordering the sides and outer end of said tray, a member of relatively stiff material loosely applied to the bottom face of said pocket and tray and made up of sections hinged to bend toward said face when pressure is applied to the sides of the casing, extensions on said member bent up from its side edges to underlie said wings, said member terminating in spaced relation with the bottom of the pocket and the outer end of the tray, and being spaced from said bottom and outer end a greater distance at the center than near the ends thereof.

7. In a coin purse, a casing of flexible material forming a coin pocket and connected tray, and a member of relatively stiff material forming a floor for said pocket and tray, said member being weakened from end to end along a plurality of longitudinal lines to bend downwardly in a predetermined manner when pressure is applied to the side walls of the casing.

In testimony whereof I have affixed my signature.

WARNER R. BUXTON.
